United States Patent Office

Des. 229,005
Patented Nov. 6, 1973

229,005

CORN DISH

Franklin S. Davis, 17 Hillview Road,
North Reading, Mass. 01867

Filed Feb. 18, 1972, Ser. No. 227,698

Term of patent 14 years

Int. Cl. D7—01, 06

U.S. Cl. D7—5

FIG. 1

FIG. 2

FIG. 1 is a side elevation view of a corn dish showing my new design;

FIG. 2 is a top view thereof;

FIG. 3 is a bottom view thereof;

FIG. 4 is a left end view thereof;

FIG. 5 is a right end view thereof; and

FIG. 6 is a cross-sectional view taken on section line 6—6 in FIG. 1.

I claim:

The ornamental design for a corn dish, as shown.
